ELECTRICAL CUT-OUT.

1,273,151.

Specification of Letters Patent. Patented July 23, 1918.

Application filed October 3, 1917. Serial No. 194,467.

To all whom it may concern:

Be it known that I, ROBERT C. COLE, a citizen of the United States, residing at Hartford, in the county of Hartford and State of Connecticut, have invented a new and useful Improvement in Electrical Cut-Outs, of which the following is a specification.

This invention relates to cut-outs of the fusible plug class in which the connection is made between the threaded shell of the plug and a contact in the threaded socket of the block by a fuse of the inclosed type.

The object of the invention is to provide a cut-out of this class which is very cheap to manufacture and assemble and which is so constructed that the fusible link is readily renewable.

When the fusible link of an inclosed electric fuse is melted by an excess current gas is generated by the volatilization of the metal, and this gas being inclosed oftentimes exerts very great internal pressure on the parts. To prevent the metal end-caps from blowing off from the tubular insulating casing under this excess pressure with liability of injury and damage therefrom it has been considered necessary to securely fasten the caps to the casing by threading the parts and screwing the caps onto the casing, or by passing pins or screws through the caps into the casing or through the caps into parts fastened to the casing.

In attaining the object of the present invention the parts are so constructed and so coöperate when in use that no means, such as threads, pins or screws, need be provided for securing the caps on the casing, in fact the coaction is such that not only are the caps held on the casing sufficiently strong to resist all internal pressure, but such close electrical contacts are made between the caps and the fusible link when the plug into which the fuse is inserted, is screwed into the socket, that all danger of heating is eliminated, and a very cheap, safe and readily renewable structure is produced.

Figure 1 of the accompanying drawings shows a central section of a fusible plug cut-out which embodies this invention. Fig. 2 shows on enlarged scale a central section of the fusible member of the cut-out. Fig. 3 shows a transverse section of the fuse on the plane indicated by the dotted line 3-3 on Fig. 2.

The cut-out illustrated has a block 1 of insulating material provided with a pocket containing a threaded metallic socket 2. This socket is connected with binding means 3 for the attachment of one wire terminal 60 and is provided with a central contact stud 4 that is connected with binding means 5 for the attachment of the other wire terminal. The central contact is insulated by a washer 6 from the end of the socket. 65

The plug consists of a cylindrical body of insulation 7 containing a metallic shell 8, the lower end 9 of which is threaded so that it may be screwed into and out of the threaded socket of the block. An insulating sleeve 10 is located within the lower end of the shell.

The fusible member of the cut-out has an insulating tube 11 which forms the casing. In a recess in each end of the opening 75 through this tube is a metallic washer 12 which has one edge cut away. These washers are loosely laid in the ends of the tube and are loosely retained in place by bending over them the ends 13 of the fusible strip 80 14 which extends through the tube and past the cut away edges of the washers. The metallic end caps 15 are made perfectly plain, that is, without threads or holes for pins or screws, and are slipped upon the 85 ends of the tube over which they loosely fit. These end caps hold the bent ends of the fusible strip against the washers in the ends of the tube. No means, such as threads, pins or screws, being provided for retaining 90 the caps in place on the ends of the tube—and the washers being loose in the ends of the tube the structure can by anyone without any tools be instantly disassembled when a strip is blown and reassembled when a new 95 strip is placed in position.

The fusible member is thrust into the plug until one cap bears against the end of the metallic shell in the insulating cylinder which forms the body of the plug. The 100 end of the other cap projects slightly beyond the end of the screw threaded portion of the shell and the insulating ring contained therein which the cap fits. A hole 16 is desirably made through the end of the 105 plug so that the fusible member may be pushed out when desired.

When the threaded shell of the plug containing the fusible member is screwed tightly into the threaded socket of the block the 110

end-caps are forced onto the tube by the engagement of one with the central contact in the socket and the engagement of the other with the closed end of the shell in the plug. This not only holds the end-caps securely in place so that they cannot be blown off from the tube by the pressure generated by the volatilization of the fusible link when melted, but this also crowds the end-caps down onto the bent ends of the fuse strip so as to firmly clamp those ends between the inner walls of the caps and the outer faces of the washers in the ends of the tube and thus insure very close joints which will eliminate the danger of heating the parts and affecting the accuracy of the fuse when the structure is in use and current is flowing across the junctions between the caps and the strip.

This construction not only eliminates all necessity of providing any means for holding the end-caps on the tube, thus cheapening the cost and rendering the device easily renewable, but owing to the freedom of the caps allows close joints to be made between them and the fusible link without the provision of means for holding the washers in exact location, as is necessary when the end-caps are screwed onto the tubular casing, owing to the fact that the casing is liable to swell and then shrink under atmospheric changes after it has been put to use.

The invention claimed is:

1. In a cut-out the combination of a threaded metallic shell, a metallic contact at an end of and connected with the shell, a threaded metallic socket for receiving the threaded shell, a metallic contact at an end of and insulated from the socket, an

insulating tube fitting within the shell 40 and having one end protruding therefrom, metallic washers loosely inserted in the ends of the tube, a fusible strip extending through the tube and having its ends bent over the outer faces of the washers, 45 and metallic caps loosely fitted on the ends of the tube, said caps being held on said tube and caused to tightly clamp the bent ends of the fusible strip between the inner walls of the caps and the washers in 50 the ends of the tube by the engagement with one cap of the contact at the end of the shell and by the engagement with the other cap of the contact at the end of the socket when the shell is screwed into the socket. 55

2. In a cut-out the combination of an insulating tube, metallic washers, loosely inserted in the ends of the tube, a fusible strip extending through the tube and having its ends bent over the outer faces of the washers, 60 metallic caps loosely fitted on the ends of the tube, a screw plug adapted to receive said capped tube, and a screw socket adapted to receive said plug, said caps being held on said tube and caused to tightly clamp the 65 bent ends of the fusible strip between the inner walls of the caps and the washers in the ends of the tube by the end walls of the shell and socket when the shell is screwed into the socket. 70

3. In a cut-out the combination of a screw socket, a screw plug adapted to be screwed into the socket, and a renewable fuse with loose end-caps, located between and having its parts held together by the socket and 75 plug when the latter is screwed into the former.

ROBERT C. COLE.
